REFRIGERATOR CABINET

Julius B. Horvay, Erie, Pa., assignor to General Electric Company, a corporation of New York

Application March 22, 1954, Serial No. 417,705

5 Claims. (Cl. 62—103)

My invention relates to refrigerator cabinets and more particularly to means for controlling the air circulation within such cabinets.

In many refrigerators the food storage compartment is cooled by means of an evaporator located in the upper portion of the compartment. Beneath this evaporator there is often positioned a transverse member which divides the compartment into an upper evaporator section and a lower fresh food section. For example, in some refrigerators this member comprises a "chiller tray" for storing foods at near but slightly above freezing temperatures whereas in others it comprises a baffle for directing air flow through the fresh food section. Whatever the purpose of this member, however, it is ordinarily designed so that a temperature suitable for the preservation of most fresh foods is maintained in lower storage section lying below it. However, it may be desirable that for some purposes a particular portion of the lower storage section be kept at a lower temperature than would normally be maintained there with this member mounted below the evaporator. For example, if vegetable pans are positioned at the very bottom of the fresh food section, it may be advantageous to supply an increased refrigerating effect to those pans to insure that the vegetables stored therein are kept fresh and unwilted.

Accordingly, it is a primary object of my invention to provide a refrigerator cabinet including new and improved air circulating means.

It is a further object of my invention to provide in a refrigerator having a transverse member mounted below the evaporator, means for maintaining a lower temperature at the bottom of the food storage compartment than would result from cooling effect set up by the transverse member alone.

Still a further object of my invention is to provide new and improved means for maintaining a low temperature in vegetable pans mounted at the bottom of a refrigerator food storage compartment.

In carrying out my invention in one preferred form thereof I utilize a refrigerator having an inner liner which defines a refrigerated storage compartment. Cooling or refrigerating means are located in the upper section of this compartment and a transverse member is disposed in the compartment beneath the cooling means. This member divides the compartment into an upper cooling section and a lower storage section and allows or causes a circulation of air effective to cool the lower storage section. In accordance with my invention I provide in this refrigerator that improvement which comprises air flow means for maintaining a low temperature in the bottom portion of the storage section of the compartment. This air flow means includes at least one vertical channel recessed in the wall of the liner. The channel extends upwardly beyond the transverse member and downwardly to the bottom portion of the storage section to form an air flow path past the transverse member leading directly from the upper cooling section of the compartment to the bottom portion. As a result, the bottom section is

2

cooled by a column of cool air dropping directly into the bottom portion through the channel and by-passing the remainder of the storage section of the compartment. In other words, through my invention a rapidly descending column of cold air is provided which maintains a low temperature at the bottom of the storage compartment without appreciably affecting the temperature of the remainder of the compartment.

The novel features which I believe to be characteristic of my invention are set forth with particularity in the appended claims. My invention, however, both as to its organization and method of operation may be best understood by reference to the following description taken in conjunction with the accompanying drawing in which:

15 Fig. 1 is a front view of a refrigerator cabinet including a preferred embodiment of my new and improved air flow means;

20 Fig. 2 is a fragmentary vertical section taken on the line 2—2 of Fig. 1; and

25 Fig. 3 is a horizontal section taken on the line 3—3 of Fig. 1.

Referring now to the diagram I have shown therein a refrigerator cabinet 1 including an outer case 2 and a spaced inner liner 3. The inner liner 3 defines a food storage compartment 4 and suitable thermal insulating material 5 is provided between the outer case and the liner to insulate the storage compartment from the surrounding atmosphere. Access to the storage compartment 4 is had by means of a suitable insulated door 6 mounted on hinges 7 and 8 at the top and bottom of the cabinet.

Provided for cooling the storage compartment 4 and located in the upper portion thereof is a cooling means or evaporator 9 which extends substantially the full width 35 of the compartment 4. During normal operation of the refrigerator a refrigerating system (not shown) supplies cold liquid refrigerant to the evaporator 9. The refrigerant effectively cools the evaporator 9 and the food storage compartment 4 by absorbing heat from the contents thereof and being thereby vaporized. During this process the warm air in the food storage compartment 4 rises toward the evaporator.

45 Disposed beneath the evaporator 9 and spaced from the underside thereof is a transverse member 10. This member 10 extends substantially across the width of storage compartment 4 to divide it into an upper or cooling section 11 and a lower or storage section 12. In my preferred embodiment illustrated the transverse member comprises a sloping baffle particularly effective for creating a rotating flow of cooling air within the storage 50 compartment. However, it should be understood that the transverse member could alternatively be a substantially horizontal "chiller" tray or receptacle for storing foods adjacent the evaporator at near freezing temperatures.

55 In my preferred embodiment any suitable means as for example the rails 13 affixed to the side walls of the liner may be used to mount the transverse baffle member 10. Further, in the illustrated refrigerator a plurality of rubber bumpers 14 are provided at the rear end of the baffle to space it slightly from the rear wall 15 of the liner 3, but it should be understood that my invention, as hereinafter described, may be also utilized to provide the same results with baffles or other transverse members whose rear edges contact the rear wall so that no appreciable gap is left therebetween. In fact, one baffle with which my invention may be utilized to produce particularly desirable results is adjustable so that the gap at the rear of the baffle may be either provided or eliminated depending upon the refrigerating effect desired in the lower portion of the storage compartment, that adjustable baffle being fully described and claimed in the co-

pending application of Harold F. Harle for "Refrigerator Baffle," S. N. 301,756, filed July 30, 1952 and assigned to the same assignee as the present invention. Also, in the illustrated refrigerator the baffle 10 is shown as including a rear pendent trough portion 16 for collecting and carrying away any moisture forming on either surface of the baffle. This trough portion, which empties into the receptacles 17 and 18 mounted in the side corners of liner 3 is however not necessary to my invention and is here shown only as a desirable feature of the baffles or other transverse members with which my invention may be utilized.

Whether the transverse member comprises a sloping baffle, as shown, or other transverse member, as a "chiller" tray, the various portions of the storage section 12 of the compartment will be normally maintained at temperatures suitable for the storage of fresh foods. For example in my preferred embodiment, due to the positioning of baffle 10 adjacent evaporator 9 it is maintained at a low temperature during the operation of the refrigerating system. As described in the aforesaid Harle application this low temperature together with the inclination of the preferred baffle causes a rotary movement of air in the storage section of the compartment. This rotary movement of air not only cools the storage section but also tends to keep the temperature differential throughout the section very low. Although exactly the same temperature cannot be held throughout storage portion, the rotary air circulation tends to minimize the differential between its various sections. If a gap is left between the rear end of the baffle and the rear wall of the liner as in the illustrated refrigerator, a somewhat lower average temperature will be maintained in the storage portion than when no gap is present due to cold air spilling through the gap, but in either case a rotary movement of air will occur to maintain a relatively even temperature throughout the storage portion.

But with or without this rotary air circulation, however, sometimes the most desirable temperature will not be maintained in a particular part of the compartment. For example, it is rather common practice to provide sliding vegetable pans in refrigerator storage compartments and in order that the contents of these pans may be kept crisp it is quite desirable that they be kept at a low temperature. With those refrigerator cabinets heretofore provided, even including the sloping baffle structure described above, it has been rather difficult to maintain these vegetable pans at the desired low temperature, particularly when they are positioned at the very bottom of the food storage compartment.

Therefore, in accordance with my invention I have provided new and improved means for providing an increased refrigerating effect in the section of a refrigerator storage compartment wherein vegetable pans or other article supporting members needing greater than normal refrigeration are positioned. Thus in my preferred embodiment there are included a pair of vegetable pans 19 and 20 needing greater refrigerating effect than they would normally receive from the air circulation set up by baffle 10. As is common in refrigerators these pans 19 and 20 are positioned at the very bottom of the storage compartment. They may be supported in any suitable manner, but are here shown as mounted by means of their upper side edges or rims. Specifically these rims are slidably received in outer guide members 21 and 22 which are affixed to the liner 3 and by a center guide member 23 which is supported by the shelf 24 positioned above the vegetable pans. This shelf 24 is preferably a solid rather than a perforated member so that it forms a barrier between the vegetable pans and the rest of the storage compartment, the reason for such barrier appearing hereinafter.

In accordance with my invention for applying an increased refrigerating effect to these vegetable pans I have provided means whereby cold air is carried directly

to the pans by-passing the remainder of the storage portion of the compartment. In the illustrated embodiment these air flow means comprise the channels or recesses 25 and 26 formed in the rear wall 15 of liner 3, the recess 25 serving to cool the vegetable pan 19 and the recess 26 the vegetable pan 20. As may be seen in Fig. 3 these recesses or channels are preferably greater in width than in depth so that they provide a relatively large cross-section for the flow of air. Further, as is best shown in Fig. 2, they extend upwardly past the rear end of the baffle 10 and downwardly to the bottom section of the refrigerator wherein the vegetable pans are positioned. More specifically, the lower ends of the channels extend downwardly below the solid shelf 24 beneath which the vegetable pans are positioned.

Through their extension above the rear end of the baffle 10, the channels 25 and 26 open into the upper cooling portion of the storage compartment wherein there is a constant supply of relatively cold air. This cold air is heavier than the somewhat warmer air in the storage portion of the compartment below the baffle and therefore tends to fall downwardly. The channels 25 and 26 form an unrestricted path or passageway for the flow of this cold air around baffle 10 and it therefore moves downwardly through them. Since there are no vanes or other air directing means obstructing flow at any point in the channels, the cold air therefore tends to move downwardly until it reaches the lower ends of the channels adjacent the vegetable pans. In other words, a column of cool air is formed in each channel which drops directly to the bottom section by-passing the remainder of the storage compartment. Due to the curved bottom ends of the channels the cool air is then discharged outwardly into the bottom section around the vegetable pans. This cold air thus flowing directly to the vegetable pan applies a much greater refrigerating effect than would otherwise there occur. For example, it has been found that through the provision of these channels the vegetable pans may be maintained from 2° to 3½° F. colder than when no such channels are provided.

As mentioned above, the shelf or cover 24 positioned above the vegetable pans 20 preferably comprises a solid rather than a perforated member. It is so made in order to prevent the vegetables stored therein from losing their moisture. Additionally, in my preferred embodiment this solid shelf 24 restricts the air flow between the vegetable pans and the remainder of the storage compartment and thus helps to prevent loss of the increased refrigerating effect supplied to the pans by my new and improved air flow means. In other words, the solid shelf, if provided, serves both as a moisture retainer and as an air flow barrier. However, even without this shelf the columns of cool air dropping through my air flow means would still be effective to maintain a low temperature in the vegetable pans.

In summation it will be seen that through my invention I have provided a simple but yet effective means whereby the bottom portion of a refrigerator storage compartment may be maintained at a temperature somewhat lower than otherwise would there be held. My air flow means for providing this result may be applied with particular advantage when it is desired to cool vegetable pans or other receptacles positioned at the bottom of the storage compartment. In the above description, I have described the air flow channels or recesses as being formed in the rear wall of the refrigerator liner and for ease of manufacture and the best results in operation it is preferable that they be so formed. However, it should be understood that, if desired, the channels may be provided in the side walls of the liner to produce the increased refrigerating effect.

Thus while in accordance with the patent statutes I have described what at present is considered to be the preferred embodiment of my invention, it will be obvious

to those skilled in the art that this and other changes and modifications may be made therein without departing from my invention, and I therefore aim in the appended claims to cover all such changes and modifications as fall within the true spirit and scope of my invention.

What I claim as new and desire to secure by Letters Patent of the United States is:

1. In a refrigerator including a liner having a rear and side walls defining a refrigerated compartment, cooling means located in the upper portion of said compartment and extending across the width thereof, and a transverse member disposed in said compartment beneath said cooling means and sloping downwardly from front to rear to divide said compartment into an upper cooling section and a lower storage section, said transverse member extending substantially across the width of said compartment and creating a rotary flow of air through said storage section for cooling said section; that improvement which comprises air flow means for maintaining a low temperature in the bottom portion of said storage section, said air flow means including a vertical channel recessed in said rear wall of said liner, said channel extending upwardly beyond said transverse member and downwardly to said bottom portion of said storage section to form an air flow path leading directly from said cooling section to said bottom portion, whereby said bottom portion is cooled by a column of cool air dropping directly into said bottom portion through said channel and bypassing the remainder of said storage section.

2. In a refrigerator including a liner having a rear and side walls defining a refrigerated compartment, cooling means located in the upper portion of said compartment and extending across the width thereof, and a transverse member disposed in said compartment beneath said cooling means and sloping downwardly from front to rear to divide said compartment into an upper cooling section and a lower storage section, said transverse member extending substantially across the width of said compartment and creating a rotary flow of air through said storage section for cooling said section; that improvement which comprises air flow means for maintaining a low temperature in the bottom portion of said storage section, said air flow means including a vertically extending recess formed in said rear wall of said liner, said recess being greater in width than in depth, and said recess extending upwardly past the rear end of said transverse member and downwardly to said bottom portion of said storage section to form an air flow path leading directly from said cooling section to said bottom portion, whereby said bottom portion is cooled by a column of cold air dropping directly into said bottom portion through said recess and bypassing the remainder of said storage section.

3. In a refrigerator including a liner having a rear and side walls defining a refrigerated compartment, an evaporator located in the upper portion of said compartment and extending across the width thereof, a transverse member disposed in said compartment beneath said evaporator and sloping downwardly from front to rear to divide said compartment into an evaporator section and a lower fresh food section, said transverse member extending substantially across the width of said compartment and creating a rotary flow of air through said fresh food section for cooling said section, and at least one vegetable pan mounted at the bottom of said fresh food section; that improvement which comprises air flow means for maintaining a low temperature in said vege-

table pan, said air flow means including at least one vertical channel recessed in the rear wall of said liner, said channel extending upwardly beyond said transverse member and downwardly below the top surface of said vegetable pan to form an air flow path leading directly from

5 said evaporator section to said vegetable pan, whereby said vegetable pan is cooled by a column of cool air dropping directly to said vegetable pan through said channel and by-passing the remainder of said fresh food section.

4. In a refrigerator including a liner having a rear and side walls defining a refrigerated compartment, an evaporator located in the upper portion of said compartment and extending across the width thereof, a transverse member disposed in said compartment beneath said evaporator and sloping downwardly from front to rear to divide said compartment into an upper evaporator section and a lower fresh food section, said transverse member extending substantially across the width of said

10 compartment and creating a rotary flow of air through said fresh food section for cooling said section, and a vegetable pan disposed in the bottom of said fresh food section; that improvement which comprises air flow means for maintaining a low temperature in said vegetable pan, said air flow means including a vertically ex-

15 tends recess formed in said rear wall of said liner, said recess being greater in width than in depth, and said recess extending upwardly past the rear end of said transverse member and downwardly to said vegetable pan to form an air flow path leading directly from said evaporator section to said vegetable pan, whereby said vegetable pan is cooled by a column of cool air dropping directly to said vegetable pan through said recess and by-passing the remainder of said fresh food section.

20 30 35 5. In a refrigerator having a liner defining a refrigerated storage compartment, an evaporator located in the upper portion of said compartment and extending across the width thereof, a transverse member disposed in said compartment beneath said evaporator and sloping down-

40 45 50 55 60 wardly from front to rear to divide said compartment into an evaporator section and a fresh food section, said transverse member extending substantially across the width of said compartment and creating a rotary flow of air through said fresh food section for cooling said section, and a vegetable pan positioned at the bottom of said fresh food section; that improvement which com-

55 prises air flow means for maintaining a low temperature in said vegetable pan, said air flow means including a vertical channel recessed in said liner and an air flow barrier positioned above said vegetable pan, said channel extending upwardly beyond said transverse member and downwardly below said barrier to form an air flow path leading directly from said evaporator section to said vegetable pan, whereby said vegetable pan is cooled by a column of cool air dropping directly to said vegetable pan past said transverse member and said barrier and by-passing the remainder of said fresh food section, with said barrier impeding air flow between said vegetable pan and said remainder of said fresh food section to restrict other air flow to said pan.
